CLAIM

We claim the ornamental design for an integrated device attachment for collar, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top perspective view of an integrated device attachment for collar in accordance with the present design; FIG. 2 is a top perspective view of the integrated device attachment for collar, shown in an expanded position; FIG. 3 is a top plan view of the integrated device attachment for collar;

FIG. 4 is a side elevation view thereof;

FIG. 5 is a bottom plan view thereof;

FIG. 6 is a top, side perspective view of the support frame component of the integrated device attachment for collar, shown separately for clarity;

FIG. 7 is a top plan view thereof;

FIG. 8 is a bottom plan view thereof;

FIG. 9 is a sectional view thereof, taken along line 9-9 as indicated in FIG. 7;

FIG. 10 is an enlarged front elevation view thereof;

FIG. 11 is a top perspective view of the latch component of the integrated device attachment for collar, shown separately for clarity;

FIG. 12 is a top plan view thereof;

FIG. 13 is a bottom view thereof;

FIG. 14 is a sectional view thereof, taken along line 14-14 as indicated in FIG. 12;

FIG. 15 is a side view thereof;

FIG. 16 is a front elevation view thereof; and,

FIG. 17 is a rear elevation view thereof.

The broken line(s) on the display screen, text, and images form no part of the claimed design.
